UNITED STATES PATENT OFFICE.

HENRY E. PHELPS, BERNARD T. KIRK, AND JOSEPH COMSTOCK, OF RIFLE, COLORADO.

ADVERTISING-MACHINE.

1,239,037.

Specification of Letters Patent.

Patented Sept. 4, 1917.

Application filed November 11, 1915. Serial No. 60,927.

To all whom it may concern:

Be it known that we, HENRY E. PHELPS, BERNARD T. KIRK, and JOSEPH COMSTOCK, citizens of the United States of America, 5 residing at Rifle, in the county of Garfield and State of Colorado, have invented certain new and useful Improvements in Advertising-Machines, of which the following is a specification, reference being had there- 10 in to the accompanying drawing.

This invention relates to an advertising machine and has for its principal object the production of a simple and efficient device for changing the advertising matter 15 so that the advertising machine may constitute an automatic changeable exhibitor.

Another object of this invention is the production of an advertising machine wherein a rotating disk is provided upon which 20 there is carried a number of plates so that as the disk rotates the advertisement on each separate plate may be brought to view, thus allowing the advertising subject-matter to be changed as desired.

25 Another object of this invention is the production of an advertising machine of the nature of a changeable exhibitor wherein a light is employed the rays of which are thrown through the advertising plates carried by the disk so as to allow the rays of 30 light to be focused upon a screen or curtain or any suitable place desired for advertising purposes.

Another object of this invention is the 35 production of an advertising machine in which a spring motor is employed which is so constructed as to intermittently rotate the disk thereby allowing the advertising matter which may be disclosed upon a screen or curtain to be intermittently changed.

A still further object of this invention is the production of an advertising machine in which the spring motor may be wound so as to run for a considerable period, al- 45 though it may be so geared as to increase or diminish the rapidity with which the rotating disk operates.

With these and other objects in view this 50 invention consists of certain novel combinations, constructions, and arrangements of parts as will be hereinafter fully described and claimed.

In the accompanying drawings:

Figure 1 is a side elevation of the com-

plete advertising machine as constructed in 55 accordance with this invention.

Fig. 2 is a rear elevation of the advertising machine constituting a changeable exhibitor.

Fig. 3 is a vertical section taken on the 60 line 3—3 of Fig. 2, looking in the direction of the arrows, portions of the spring motor being removed.

Fig. 4 is a section taken on the line 4—4 of Fig. 3, looking in the direction of the 65 arrows.

Fig. 5 is a top plan view of the spring motor, the rotating disk and shaft therefor being broken away and partially disclosed in section.

Fig. 6 is an elevation of a certain cam wheel and the cam therefor.

Fig. 7 is an enlarged fragmentary rear elevation of a portion of the rotating disk, illustrating the manner in which the glass 75 plates or slides are used and supported.

Fig. 8 is a longitudinal section through the focusing hood.

Fig. 9 is a section taken on the line 9—9 of Fig. 8.

Fig. 10 is an elevation of the spring motor, the rear plate of the casing therefor being removed.

Fig. 11 is a sectional view through a portion of the spring motor.

Fig. 12 is a detail of a certain lever used in connection with the spring motor.

Referring to the accompanying drawing by numerals it will be seen that the main casing comprises a rear wall 1 which is preferably circular in shape, as disclosed clearly in Fig. 2, having the enlarged web 2 formed upon its lower portion. The base block 3 is fixedly mounted upon this web 2 and carries the hinges 4 to which the front wall 5 is secured. The side portions of the walls 1 and 5 are covered by means of the metallic strips 3', thereby inclosing the casing. By thus mounting the front wall it will be seen that it may be swung outwardly for allowing access to the interior of the main casing.

Since the web 2 is comparatively broad across its base portion as shown in Figs. 2 and 4, it will be seen that when the advertising machine is positioned upon a support 105 it will be retained from turning over on its side portions. The upper portions of the walls 1 and 5 are provided with rectangular

shaped sockets 6 in which rests the rectangular tube 7. It is, of course, obvious that this tube may be made in any desired shape, but as disclosed herein it is rectangular in 5 cross-section for more efficiently and positively retaining the same in its correct position upon the upper portions of the main casing. This tube 7 is elongated, as is very clearly disclosed in Figs. 1 and 2, and has 10 a cap 8 mounted upon its rear end. A reflector 9 is carried by the cap 8 so as to fit within the tube 7 in the rear portions of the electric lamp 10. Therefore, it will be seen that when in operation the rays from the 15 lamp 10 will be reflected by the reflector 9 to the forward portions of the tube 7. The focusing hood 11 having the glass 12 in its forward end is, of course, round and tapers toward its forward portions so as to properly focus the rays of light when the advertising machine is in use. The squared rear portion 13 of the hood 11 fits upon the tube 7 and, therefore, it will be seen that the focusing hood 11 will be correctly supported. 20 Since, however, this hood fits snugly upon the tube 7 although it will be held from accidentally disengaging the tube, it may be readily adjusted for properly focusing the rays of light upon the screen or curtain upon 25 which the advertising matter is to be disclosed.

The main drive shaft 14 is carried by the rear wall 1 and extends for a distance upon each side of this rear wall 1. Since the 30 forward end of the main drive shaft 14 extends into the space between the rear and front walls 1 and 5 respectively, as shown clearly in Fig. 3, the circular disk 15 is carried thereon, this disk being retained in position by means of the clamping washers 16 mounted upon the side thereof and being carried by the shaft 14. This disk 15 extends between the rear and forward walls and also extends into the tube 7, since this 35 tube 7 is provided with the slot 17, as shown in Figs. 3 and 4. Thus, it will be seen that when rotary motion is imparted to the disk 15 by means of the drive shaft 14 the disk may be freely rotated within the main housing and also will pass through the tube so that the rays of light from the lamp 10 will be reflected upon this disk. This disk 15 is 40 also provided with a number of openings 18 formed therein adjacent its periphery, these 45 openings 18 being of any suitable shape desired although disclosed rectangularly in the drawings. The tracks 19 are fixedly mounted upon the rear surface of the disk 15 as shown clearly in Figs. 3 and 7 so as to allow 50 the plates or slides 20 to be carried thereby. These plates or slides 20 are adapted to be retained in engagement with the disk 15 so as to cover the openings 18 formed therein, and since the tracks 19 are adapted to fric-

tionally engage the plates 20 it will be seen 65 that these plates will be held against accidental displacement when the device is in operation. Accordingly, when the advertising machine is in use the rays of light will reflect through the plates or slides 20 upon 70 which the advertising matter is placed so as to cause the rays of light to be focused correctly by means of the hood 11 and be thrown upon a screen or curtain whenever desired for the purpose of advertising the 75 subject matter contained upon each plate or slide 20.

The spring motor used in connection with this advertising machine for driving the shaft 14 is carried within the housing 21 which is fixedly secured in any suitable manner upon the outer portions of the rear wall 1. The brackets 22 are secured to the inner portions of the housing 21 so as to support the rear side 23 of the frame of the motor. The bars 24 extend from the rear side 23 of the motor and the front side 25 therefor, thereby producing a supporting frame for the motor in which the side portions are permanently retained in parallel 80 spaced relation. The main drive shaft 14 extends so as to be carried by the sides 23 and 25 of the motor supporting frame, as shown clearly in Figs. 3 and 10. A pinion 26 is keyed upon the shaft 14 between the 85 sides of the frame, while the ratchet wheel 27 is keyed upon the outer end of the shaft 14. In order to impart rotary motion to the shaft 14 the gear 28 meshes with the gear 26, while the auxiliary gear 28' secured to the gear 28 meshes with the drive gear 29 of the spring 30. The shaft 31 upon which the gears 28 and 28' are mounted is provided with a grip portion 32 so that when so desired the shaft 31 may be rotated 90 for winding the coiled spring 30. In order to check the movement of the disk 15 the gear 33 meshes with the gear 28 and is fixedly mounted upon the shaft 34 carrying the gear 35. This gear 35 is retained against 95 unlimited rotation by means of the latch 36 carried by the locking shaft 37 from which extends the trip arm 38. Furthermore, there is provided a releasing lever 39 having 100 a claw end 40 for engaging the ratchet wheel 27. This lever 39 is pivotally mounted 105 upon the bracket portion 41 carried by the front side 25 of the motor supporting frame. This lever 39 is normally urged in 110 one direction by means of the coiled spring 42 secured to the shaft 31 and to the forward end of the lever 39. Thus, it will be seen that the claw 40 of the lever 39 will be 115 normally retained in engagement with the ratchet wheel 27 thus limiting the rotary movement of this wheel. In order to release the ratchet wheel 27 and the gear wheel 35 for allowing the shaft 14 to be driven for 120

a desired period for rotating the disk 15 there is provided a main spring 43 for driving the tripping mechanism. This main spring is carried upon the shaft 44 which is supported upon the motor supporting frame, and this spring 43 is keyed in any suitable manner to the gear 45. Upon the shaft 46 there is carried the primary gear 47 and auxiliary gear 48. This auxiliary gear 48 meshes with the gear 45 of the spring 43 and consequently, the spring 43 will impart rotary movement to the shaft 46 by means of the gears 45 and 48. When the shaft 46 is rotated it will be seen that rotary motion will be imparted to the gear 48 which will in turn impart rotary motion to the auxiliary gear 49 of the check gear 50. The timing pawl 41 is carried upon the upper portion of the motor supporting frame by means of the shaft 52 so as to engage the gear 50. The timing arm 53 is secured to the pawl 51 and extends for a considerable distance thereabove, as shown in Fig. 10. This timing arm 53 extends between the pins 54 of the pendulum arm 55 which pendulum arm is secured by a bracket 56 or any suitable securing means in spaced relation to the rear wall 1. Thus it will be seen that as the pendulum 55 swings to and fro the arm 53 will also rock in the direction in which the pendulum is swinging thus permitting the gear 50 to rotate with a reduced speed. The weight 57 is slidably or adjustably mounted upon the pendulum 55 so that when the weight is moved upwardly the speed with which the pendulum 55 swings will be increased or when the weight is moved downwardly the speed will be decreased, thus allowing the speed with which the gear 47 imparts rotary motion to the gear 58 of the cam shaft 59 to be increased or diminished. This cam shaft 59 is carried by the forward and rear walls 25 and 23 and is provided upon its outer end with the cam 60, while adjacent its inner end there is carried the trip wheel 61. This trip wheel 61 is provided with a notch 62 in its periphery so that as it rotates the free end of the trip arm 38 may be passed thereinto. As the shaft 59 rotates the cam 60 will come into engagement with the offset end 63 of the lever 38 so as to lift the claw 40 from engagement with the ratchet wheel 27 at the same time the trip arm 38 rests within the notch 62, whereby the pawl 51 will be released. The gear 37 will also be released by this action since the tripping of the arm 38 will allow the latch 36 to be swung far enough to allow the gear 37 to be freed for an instant thus allowing the spring 30 to impart rotary motion through its train of gears to the shaft 14, whereby the disk 15 will be rotated. Of course, as the continued operation of the arm 53 allows ro-

tary motion to be imparted to the shaft 59 it will be seen that the cam 60 will release the lever 38 while the trip arm 38 will ride upon the outer periphery of the trip wheel 61, thus again locking the gears driven by the spring 30 so as to allow the disk to remain stationary. At this time one of the plates will be in a position to allow the rays of light to reflect therethrough for permitting the subject-matter of a sign which may be carried upon a plate or slide 20 to be reflected upon a desired screen or curtain. Of course, it is obvious that upon the adjusting of the weight 57 the speed of the motor may be increased or decreased so that the intermittent rotation of the disk 15 may be increased or decreased in speed as desired.

From the foregoing description it will be seen that a very efficient advertising machine has been provided in the nature of an automatic changeable exhibitor which is so constructed as to allow the motor thereof to intermittently drive the rotating disk for allowing the subject-matter of the signs carried thereby to be reflected upon a screen, while the front wall of the main casing may be swung to an open position for allowing a new disk to be substituted or allowing the old disk to be removed so as to position new plates upon the brackets 19. Furthermore, it is obvious that by the present construction the advertising machine will continue to operate as long as the springs are wound sufficiently to drive the same, so that the signs may be automatically changed at predetermined intervals.

What is claimed is:

1. In an advertising machine of the class described, the combination of a casing, said casing comprising a rear wall and a forward wall, a base block carried by said walls for retaining said walls in parallel spaced relation, said forward wall being hingedly secured to said base, a tube carried upon said walls, a rotating disk carried between said walls and extending into said tube, said disk being adapted to contain advertising matter, means for reflecting rays of light upon the advertising matter of said disk, means for rotating said disk whereby the subject-matter of the advertisement may be reflected through said tube upon a screen or curtain carried in front of said tube, said forward wall being capable of being swung to an open position so as to allow said disk to be removed when necessary.

2. In an advertising machine of the class described the combination of a casing comprising a forward wall and a rear wall, said walls being substantially circular in shape and having webs formed upon their lower portions, a base block carried by said webs so as to retain said walls in parallel spaced relation, said walls provided with

rectangular pockets in their upper portions, an elongated tube fitting within said pockets, said tube provided with a slot formed in alignment with the inner portions of said walls, a disk positioned within said casing and extending through the slot formed in said tube, means for intermittently rotating said disk, said disk being adapted to carry advertising matter thereon, means for reflecting rays of light upon the advertising

matter in said disk whereby the subject-matter of the advertising matter may be thrown upon a screen or curtain carried in front of said tube.

In testimony whereof we hereunto affix 15
our signatures.

HENRY E. PHELPS.
BERNARD T. KIRK.
JOE COMSTOCK.
